UNITED STATES PATENT OFFICE.

FRANK J. LOWERY AND FRANK EVERETT BILLINGS, OF FORT FAIRFIELD, MAINE.

SASH BALANCE AND FASTENER.

SPECIFICATION forming part of Letters Patent No. 714,720, dated December 2, 1902.

Application filed March 26, 1902. Serial No. 100,107. (No model.)

To all whom it may concern:

Be it known that we, FRANK J. LOWERY and FRANK EVERETT BILLINGS, citizens of the United States, residing at Fort Fairfield, in the county of Aroostook and State of Maine, have invented certain new and useful Improvements in Sash Balances and Fasteners; and we do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in window-sash balances and fasteners, and comprises means whereby the spring-actuated gear-wheel carried in a suitable casing is held from rotation and also a spring-actuated bolt adapted to be held in engagement with a rack-bar in the edge of the screen, said bolt adapted to be actuated, by means of a push-button, to throw the same out of engagement with the rack-bar simultaneously with the operation of the locking means, whereby the said spring-actuated gear-wheel is allowed to rotate.

The invention consists, further, in the provision, in connection with a sash-fastener, of a guide-bar secured to one sash and adapted to have bearing or a ball which is adapted to travel in a casing mounted in the adjacent frame.

The invention comprises various other details of construction, which will be hereinafter fully described and then specifically defined in the appended claims, and is illustrated in the accompanying drawings, which, with the letters of reference marked thereon, form a part of this application, and in which drawings—

Figure 1 is an elevation of our device shown as applied to the sash and frame of a window. Fig. 2 is a vertical cross-sectional view through a portion of the casing and sash, showing the push-button for releasing the locking mechanism carried by the screen. Fig. 3 is an enlarged detail view of the spring-actuated bolt which locks the gear-wheel. Fig. 4 is a detail view of the push-button. Fig. 5 is a sec-

tional view horizontally through the casing, showing in top elevation the ball-carrying plate. Fig. 6 is an enlarged detail perspective view of the antifriction-ball and the member carrying the same. 55

Reference now being had to the details of the drawings by letter, A designates the sash of a window-screen, on the edge of which is provided a rack-bar B, having a series of teeth on its outer edge. Adjacent to said rack-bar is a casing C, which is countersunk in the frame of the window. In said frame is journaled a shaft D, to one end of which is secured a spring B', the outer end of said spring being connected to the gear-wheel E near its periphery. Said gear-wheel has a number of gear-teeth disposed along its periphery which are in mesh with the teeth of the rack-bar B. 65

Mounted to slide horizontally on the upper surface of the lower portion of the casing is a bolt F, the forward end of which is guided through an aperture in the wall of the casing adjacent to the rack-bar, and the outer end of said bolt is adapted to engage between the teeth of said rack-bar to normally hold the sash locked. Said bolt F has an elongated aperture F' through the body portion thereof, and a spring G, carried by the bolt K, 70 bears yieldingly against a shoulder f on the bolt, which is adapted to hold said bolt normally in a locked relation with the rack-bar. The inner end of said bolt F has an inclined edge, as at F², which is adapted to engage in 75 a recess H in the end of a spring-actuated bolt K.

A spring N, fastened at one end, as at N', to the casing, bears yieldingly against the upper end of the bolt K and is adapted to 80 hold the same normally in the position shown in Fig. 1 of the drawings, in which position the tapering end of the head F² of bolt F is in contact with the tapering wall of the recess in the end of the bolt K. Projecting laterally 85 from the upper end of the bolt K is a lug or stop K', which when in locking relation is disposed in the path of the teeth of said gear-wheel, preventing said wheel from rotating.

M designates a push-button having a laterally-projecting portion M', which has an inclined edge M², which laterally-projecting

- portion is adapted to be inserted in the elongated slot in the bolt F for the purpose of having a wedging action against the end of said elongated aperture when it is desired to 5 actuate the bolts longitudinally to throw the same out of engagement with the rack-bar and cog-teeth, respectively. The inner end of said push-button is contracted, as at O, and is adapted to enter an aperture P in the 10 wall of the casing, while the outer shank portion of the push-button has a thumb-piece or free end Q projecting through the finishing-strip R of the window-frame. A casing S is seated in said finishing-strip R, and a spring 15 S' is provided, which is seated in said casing S and bears between the inner end of the casing and the enlarged outer end Q, serving to throw said push-button normally out of engagement with the spring-actuated bolt F.
- 20 Mounted in a channel in the frame of the window is a casing T, which is flanged, as at T', on its inner longitudinal portion, and behind said flange an antifriction-ball J is adapted to bear, said ball being held by means of 25 a socket I, which is formed at the end of a bracket-arm I', held to the sash at any suitable location. When said ball is adjusted in position and held by the socket member, it has a frictional contact with the inner face 30 of said flange, adapted to bear against the same as the window is raised and lowered. Said bracket-arm has a recess L adjacent to its socket end, in which the free edge of the flange fits, as clearly shown in the drawings.
- 35 Having thus fully described our invention, what we claim as new, and desire to secure by Letters Patent, is—
1. A sash balance and fastener comprising in combination with the sash, a rack-bar on 40 the ends thereof, a casing seated in the frame of the window, a shaft mounted in said casing, a spring-actuated gear-wheel mounted on said shaft and in mesh with said teeth, spring-actuated bolts arranged at right angles 45 to each other, one of which bolts is adapted to engage said rack and the other the teeth of the gear-wheel, and a push-button for actuating said bolts simultaneously, as set forth.
2. A sash balance and fastener comprising 50 in combination with the sash of a window, a rack-bar on the edge thereof, a casing seated in the frame of the window, a shaft journaled on said frame, a spring-actuated gear-wheel mounted on said shaft and in mesh with said 55 rack-bar, a spring-actuated bolt mounted in
- said casing and normally in engagement with the teeth of the rack-bar, a second spring-actuated bolt having a projection on one side thereof adapted to normally rest in the path of the teeth of said gear-wheel, a push-button adapted to actuate longitudinally the bolt engaging the rack-teeth, the head of which bolt is designed to throw the second bolt out of the path of the teeth of the gear-wheel, as set forth. 60 65
3. A window-sash balance and fastener, comprising in combination with the sash of a window, a rack-bar on the edge thereof, a casing seated in the window, a spring-actuated gear-wheel mounted therein and in engagement with the teeth of the rack-bar, a spring-actuated bolt F in said casing adapted to engage the teeth of said rack-bar, and having a head with an inclined edge, a second bolt, spring-actuated and having a recessed 70 end, one wall of which is inclined against which the inclined end of said bolt is adapted to contact, a lug projecting laterally from the second bolt, and normally in the path of the teeth of said gear-wheel, a spring secured to 75 the casing at one end and bearing yieldingly against said projecting portion, and a push-button for actuating said bolt F, as set forth.
4. In combination with a sash, a rack-bar mounted thereon, a casing, a spring-actuated 80 gear-wheel mounted in said casing, a bolt F, spring-actuated and adapted to engage the teeth of said rack, a shouldered portion on said bolt, and a head with an inclined edge, a bolt K with a projecting portion K' on one 85 end, the opposite end of said bolt K being recessed, one end of said recess having an inclined wall adapted to engage the inclined edge of said bolt F, a push-button having a laterally-projecting portion with an inclined 90 edge, which is adapted to enter an elongated aperture in said bolt F and bear against the end of said aperture, the inner contracted end of said button designed to engage an aperture in said casing, and a spring for normally holding said button at its farthest outward throw, as set forth. 95 100

In testimony whereof we hereunto affix our signatures in presence of two witnesses.
